WHEEL BALANCER MOUNTING RING

George T. Hemmeter, Los Altos, Calif.

Application July 14, 1958, Serial No. 51,773

Term of patent 14 years

(Cl. D55—1)

FIG. 1

Des. 184,619

PAGE 2

FIG-2

FIG-3

FIG. 4

FIG. 5

Figure 1 is a perspective view of the wheel balancer mounting ring, showing my new design;

Figure 2 is a top plan view thereof;

Figure 3 is a side elevation thereof;

Figure 4 is a bottom plan view thereof; and

Figure 5 is another side elevation thereof taken 180° from Figure 3.

I claim:

The ornamental design for a wheel balancer mounting ring, as shown.
